UNITED STATES PATENT OFFICE.

EMIL CHRISTENSEN, OF PORTLAND, OREGON, ASSIGNOR OF ONE-HALF TO
IGNATZ WISLER, OF SAME PLACE.

MACHINE FOR CONNECTING BUTTON SHANKS AND FASTENERS.

SPECIFICATION forming part of Letters Patent No. 500,993, dated July 4, 1893.

Application filed January 9, 1893. Serial No. 457,801. (No model.)

To all whom it may concern:

Be it known that I, EMIL CHRISTENSEN, a citizen of the United States, residing at Portland, in the county of Multnomah, State of Oregon, have invented certain new and useful Improvements in Machines for Connecting Button Shanks and Fasteners, of which the following is a specification, reference being had therein to the accompanying drawings.

10 This invention relates to machines used in attaching buttons; and the objects of this improvement are to provide a machine of simple and inexpensive construction to automatically connect a staple with the shank of each 15 button preparatory to its attachment to a piece of leather or of fabric. I attain these objects by the construction illustrated in the accompanying drawings, in which—

Figure 1 is a perspective view of a button-stapling machine constructed in accordance 20 with my invention. Fig. 2 is a longitudinal vertical section of the same on line xx of Fig. 3. Fig. 3 is a transverse vertical section of the machine on line yy of Fig. 2, showing the 25 hooked point of the staple-advancing lever at the upper end of its course as when the front end of the button and staple-holding box is depressed as shown in Figs. 1 and 2. Fig. 4 is a transverse vertical section of the 30 same on line zz of Fig. 2 showing the hooked point of the staple-advancing lever at the lower end of its course as when the front end of the button and staple-holding box is elevated. Fig. 5 represents in perspective the 35 inner side of the race-way for the staples and for the hooked end of the staple advancing lever. Fig. 6 represents in perspective a portion of the inner side of the front plate of the frame showing a vertical groove to guide the 40 front end of a pivoted rod used to operate the staple and button advancing devices; and also horizontal grooves to guide said button controlling and advancing device. Fig. 7 is a perspective view of the staple advancing 45 lever. Fig. 8 is a perspective view of the button controlling and advancing device and of a portion of its operating lever. Fig. 9 is a top view of the button controlling and advancing device. Fig. 10 is a perspective view 50 of the front end of the button race-way. Fig.

11 is a perspective view of the brush carrying plate to control the escape of the button at the time it receives its staple. Fig. 12 is a side view of the button-shank connecting machine mounted upon the button setting 55 machine represented in Patent No. 309,080, of December 9, 1884.

In said drawings the frame of the machine consists of a front plate A, having rearwardly extended therefrom two wings A² united in 60 their front portions by a transverse plate A³. These parts are generally cast together in one piece, and said transverse plate has vertical perforations a³ to receive screws by which the frame is secured to the top of the stand- 65 ard of a button setting machine, (for example the machine known in the market as the “Trojan”) in place of the grooved button-feeding tube usually found in that class of machines.

To the rear portion of the two wings A² of the frame, a box B is pivoted at b. The front portion of said box is adapted to be vertically oscillated by means of a connecting rod C adjustably connected with the rear end of said 70 box, adjacent to the pivot b. The lower end of said rod is to be connected by means of a bell crank lever or other suitable means with the vertically operating rod of the button- 75 setting machine, said rod being usually connected with a treadle at the bottom thereof.

To adjust the length of the rod C to variously constructed button-setting machines, its lower end is screw-threaded and received into a socket c having its lower end forked to embrace and be connected with the bell-crank lever. The upper end C is also provided with a forked socket that is pivoted to the head of a screw c² adjustably secured to the bottom of the box B. This box is to receive a 80 supply of buttons b² and has its front portion partitioned off to form a box B² to receive a supply of button-staples b³. The bottom and also the front of the box B have slots to permit it to be vertically oscillated against the 85 sides of the stationary button race-way D, and of the stationary staple guide-plate E. The grooved race-way D is secured by its lower edge to the top of the transverse plate A³ of the frame; but the guide plate E has 90 95 100

its front edge secured to the front plate A of the frame by a small angle plate e. The upper edge of the race-way B has a groove d the whole length thereof to receive the shanks 5 of the buttons lodged thereon from the supply in the box B, at each oscillation of the latter. The front end of the raceway D, is provided with a thin narrow plate d² secured thereto on each side thereof by flanging down- 10 wardly the rear portion of said plates. The front ends of the plate d² are made to extend through an opening in the front plate A of the frame and they are kept apart to form a groove d³ between them in continuation with 15 the groove d, to direct the buttons that have been provided with a staple, under the plunger of the button-setting machine.

To permit the buttons received in the inclined race-way D to slide down said race-way and out of the front end of the box B, there is in said front end near the top thereof of an opening b⁴ of sufficient size for the passage of said button when said front end has nearly reached the lower end of its oscillation. After the buttons have left the box B, they are prevented from leaving the groove d³ by means of narrow plate f located above, and nearly in contact with the buttons. Said plate f is made to pass through an opening 20 in the front plate A of the frame, and has its front end bent upward and adjustably secured to the outer face of the plate A by means of a screw f² passing through a slot f³ in the upwardly bent end of the plate f. 25 The forward portion of the plate f carries pendent therefrom a tuft of hair or of fine bristles f⁴ to temporarily arrest the buttons in the groove d³ of the inclined race-way, the button in contact with the side of the bristles 30 f⁴ having then, its shank in proper position to receive a staple advanced laterally therein. The rear end of the plate f is also bent upward at f⁵ to form a shield for the front end of the box B. The rear portion of the plate 35 f is steadied against lateral displacement by means of a sheet metal strip f⁶ that has its lower ends secured to the race-way D. After the button-shank has received its staple, it is forced forward beyond the tuft of bristles by 40 a beveled point or plow-share shaped finger g carried on top of a carriage G that is adapted to be moved transversely across the rear face of the front plate A of the frame. This carriage is mounted upon a shelf a projecting 45 rearwardly from the bottom edge of said plate A. The front edge g² of the carriage is received into a groove a' formed longitudinally in the plate A above its shelf a to prevent it from being lifted by the members that recip- 50 rocate it. The carriage G also carries a cut-off plate g³ to arrest the row of buttons sliding along the race-way until the front one is needed to be advanced by the beveled finger g. Said carriage carries also horizontally a 55 sheet metal finger g⁴ that has a V shaped point to enter the wire loop or shank of one of the buttons and positively guide and retain it in

proper position for one of the branches of the staple to enter said shank. Room to operate said finger g⁴ is obtained in a horizontal groove 70 a' formed in the plate A of the frame.

To reciprocate the carriage G, and also to give at the same time an oscillating rotation to a pivoted lever H used to positively advance each staple into the shank of a button, 75 there is pivoted at a' to the upper end of one of the wings A² of the frame, a rod I, that is thus located along-side of the box B and has its front portion vertically oscillated by said box, by coming in contact with projections, or 80 preferably rollers i i² projecting from the side of the box B, one above, and one under said rod I. The front portion of the rod I is made to pass through a slot k formed in a lever K having its lower end pivoted upon a pin k² 85 projecting from the front edge of the transverse plate A³ of the frame, and also through a slot h made lengthwise of the lever H. The front end of the rod I terminates into a vertical groove A' formed in the front plate A, 90 whereby it is properly guided and permitted to oscillate the carriage G horizontally, and the lever H around the pivot h², said carriage G being connected to the lever K by means of a link k³. 95

To bring the staples b³ from the top of the inclined guide plate E, to, and through the looped shanks of the buttons said staples are allowed to pass through an opening l in a plate L secured to the inner face of the front plate A of the frame. Said opening leads the staple into a segmental groove l² formed into said plate L. The lower end of said groove terminates at a point in front of the cut-off g³ and under the tuft of bristles f⁴. Each staple 105 drops into the groove l² with its two prongs downward, but as said groove is in the form of a quarter of a circle, when the staple reaches the lower end of the groove, it is held horizontally with its upper prong in the proper 110 position to enter the shank of the button that has been brought to that point as before stated. 115

To positively advance the staple in the groove l² until it has been received by the shank of the button, the lever H is used; its end h² is curved in the form of a hook to travel in said groove l², a notch h³ being cut into the side of the lever to straddle the segmental portion of the metal between the groove l² and the inner edge of the plate L. To prevent the staples b³ from being fed too rapidly into the groove l², but to cause them to be dropped one by one, two latches m and m² placed nearly side by side, are made to rest upon the 120 guide plate E by means of springs m³ pressing upon said latches, the latter having one end pivoted at m⁴ to the plate L. To elevate the opposite end of said latches at different times, one after the other, the lever H has projecting from its face two pins h³ and h⁴ about equidistant from the pivot pin h² of said lever. The pin h³ is to elevate the latch m as shown in Fig. 4 and permit one of the staples 125 130

to slide down the guide plate E to the side of the latch m^2 where it becomes arrested, until the lever H is swung around to the position shown in Fig. 3. Then the pin h^4 lifts the latch m^2 and permits the staple to advance upon, and drop from the end of the plate E, into the guide-groove l^2 .

5 The box B is provided with a rectangular sheet metal cover N that has side lugs n to receive pivot pins or screws secured in the upper ends of the two wings of the frame. Said cover is to prevent the buttons and their staples from being accidentally jerked out of their respective boxes B and B^2 , when said 15 boxes are suddenly arrested in their upward movement.

Having now fully described my invention, I claim—

1. In a machine for connecting buttons to 20 their staples, the combination of a frame adapted to be secured to a button setting machine, a rectangular box for buttons and fasteners having its rear end pivoted to said frame and two slots in its bottom, a straight 25 race-way for the buttons and a staple guide-plate received in said slots, and a connecting rod adjustably secured to said box substantially as described.

2. The combination of a frame adapted to 30 be secured to a button setting machine, a straight race-way secured to said frame and having a groove in its top for the reception of the shanks of buttons, a rectangular box for buttons and fasteners pivoted at its rear end 35 and having a slot in its bottom to receive the race-way, narrow plates d^2 secured to the front end of the race-way and extended through the front end of the frame, and a button retaining plate f above said raceway substantially 40 as described.

3. The combination of a frame adapted to 45 be secured to a button setting machine, a straight race-way secured to said frame and having a groove in its top, a rectangular box pivoted at its rear end and having a slot in 50 its bottom to receive the race-way, narrow plates d^2 secured to the front end of the race-way, a button retaining plate f above said race-way, and a tuft of bristles pendent from said plate f substantially as described.

4. The combination of a frame adapted to be secured to a button setting machine, a race-way for the buttons, a box pivoted at its rear end and having a slot in its bottom to receive the race-way, and rollers i^2 on its side, a rod 55 I pivoted to the frame and passing between said rollers, a slotted lever K in engagement with the rod I, and a horizontally movable carriage G linked to the lever K and having a cut-off plate g^3 to arrest the buttons substantially as described.

5. The combination of a frame adapted to be secured to a button setting machine, a box pivoted at its rear end to said frame and having rollers on the side, a rod I pivoted to the 65 frame, a slotted lever K in engagement with the rod I, and a horizontally movable carriage G linked to the lever K, said carriage having a cut-off plate g^3 on top thereof, a beveled plane g and a pointed finger g^4 substantially 70 as described.

6. The combination of a frame adapted to be secured to a button setting machine and a staple guide-plate E secured to said frame, a box pivoted at its rear end to said frame, a 75 rod I pivoted also to said frame and connected to the side of said box a pivoted lever H having a slot at one end in engagement with the rod I and a hook at the other end, and a plate L having a segmental groove to receive the 80 staples from the guide plate E substantially as described.

7. The combination of a frame adapted to be secured to a button setting machine and a staple guide-plate E secured to said frame, 85 a box pivoted at its rear end to said frame, a rod I pivoted also to said frame and connected with the side of said box, a pivoted lever H having a slot at one end in engagement with the rod I and pins h^3 h^4 projecting from said 90 lever, with pivoted latches resting upon the plate E and adapted to be lifted therefrom by said pins h^3 h^4 substantially as described.

In testimony whereof I affix my signature in presence of two witnesses.

EMIL CHRISTENSEN.
